Specification for Design.

Patented Aug. 26, 1913.

Application filed May 7, 1913. Serial No. 766,192. Term of patent 7 years.

To all whom it may concern:

Be it known that I, CHARLES F. GARNISSL, a citizen of the United States, residing at Bridgewater, in the county of Plymouth and State of Massachusetts, have invented a new, original, and ornamental Design for an Advertising-Cabinet, used for advertising and decorative purposes, of which the following is a specification, reference being had to the accompanying drawing, forming a part thereof.

The figure is an elevation of an advertising cabinet, showing my new design.

I claim:

The ornamental design for an advertising cabinet, as shown.

CHARLES F. GARNISSL.
